William G. Lindemann

By R. S. Caldwell
Attorney.

UNITED STATES PATENT OFFICE.

WILLIAM G. LINDEMANN, OF MILWAUKEE, WISCONSIN, ASSIGNOR TO OZONE COMPANY OF AMERICA, OF MILWAUKEE, WISCONSIN, A CORPORATION OF DELAWARE.

COMBINED FAUCET AND SWITCH.

1,375,099.

Specification of Letters Patent. Patented Apr. 19, 1921.

Application filed February 15, 1919. Serial No. 277,294.

To all whom it may concern:

Be it known that I, WILLIAM G. LINDEMANN, a citizen of the United States, and resident of Milwaukee, Milwaukee county, 5 Wisconsin, have invented new and useful Improvements in Combined Faucets and Switches, of which the following is a description, reference being had to the accompanying drawings, which are a part of 10 this specification.

The invention relates to an electric switch and to a means for actuating the switch simultaneously with the turning on of a water faucet, and is more particularly designed for use in connection with apparatus 15 for supplying ozonized water for drinking or other purposes.

One of the objects of the invention is to provide a simple and efficient form of push 20 button switch and means for detachably securing it to a suitable support.

Another object of the invention is to provide a combined switch and faucet-actuating means so that current may be supplied 25 to an ozonizing apparatus simultaneously with the turning on of the water to be ozonized.

The invention further consists in the several features hereinafter set forth and more 30 particularly defined by claims at the conclusion hereof.

In the drawings:

Figure 1 is a perspective view of the device embodying the invention applied to 35 an ozonizing apparatus;

Fig. 2 is a vertical sectional view through the device;

Fig. 3 is a section taken on the line 3—3 of Fig. 2;

Fig. 4 is a section taken on the line 4—4 of Fig. 3;

Fig. 5 is a section taken on the line 5—5 of Fig. 3.

In the type of ozonizing apparatus in connection with which the invention is adapted 45 to be used, an air ozonizing apparatus and a water filter, neither of which is specifically shown, are disposed in a cabinet 6.

The water pipe 7 from the filter leads to 50 a coupling 8 and the pipe 9, for conducting ozonized air, leads to said coupling. The ozonized air and water are brought together in the coupling 8 which forms part of the mixing device. This is done by the

process of aspiration carried out by nozzles 55 10 and 11 which are spaced apart so that the ozonized air from the pipe 9 is drawn into the pipe 12 through nozzle 11 by the water passing through nozzle 10 and also carried out by the nozzle 13 on the pipe 12 60 spaced from the upper end of a pipe 14, the ozonized air, passing down through openings 15 into a chamber 16 and thence through the annular orifice between the nozzle 13 and the pipe 14, being sucked into said pipe 14 65 by the flow of the water. The ozonized water passes down through the pipe 14 and a fine mesh screen cap 17 into a closed tube 18 having outlets 19 at its upper end through which the ozonized water passes into the 70 upper chamber 20 of a nozzle 21 and thence through the screen 22 to the outlet end 23 of the nozzle. This mixing of the ozonized air with the water does not constitute a part of the present invention. 75

The push button switch forming a part of the present invention consists of a block 24 of insulating material having a contact housing cavity 25 therein, a bore 26 at one end connected by the bore 27, of smaller diameter, with the cavity 25 and an opening 28 at its other end through which conductors 29 and 30 pass, said conductors being for the passage of electric current to the ozonizing apparatus. The cavity 25 has inclined 85 sides 31 and 32 and contact plates 33 and 34 are respectively secured thereto by screws 35 and binding post screws 36 to which the conductors 29 and 30 are connected.

The contact plate 33 is of spring metal 90 having a resilient contact finger 37 cut and bent outwardly therefrom, and the contact 34 is of spring metal having a resilient contact finger 39 cut and bent outwardly therefrom. The end 40 of the finger 37 has a 95 wiping contact with the finger 39 when pressed inwardly.

The finger 37 is normally out of engagement with the finger 39 and is adapted to be moved into contact therewith by a push 100 button 41, normally held in inoperative position by means of a spring 42 interposed between an annular shoulder 43 in the block and a shoulder 44 on the button, movement of the button being limited by a cap 45 having a tight fit in the bore 26. The inner end of the button is slidably mounted in the bore 27 and an inward pressure on said but- 105

ton causes said inner end to engage the finger 37 and move it into contact with the finger 39.

The block is protected on three sides by a 5 channel plate 46 tightly fitting against the sides of the block and having extensions 47 provided with inwardly extending flanges 48 whereby the switch may be secured to a support having grooves therein to receive 10 the flanges, as the grooves 49 in the pipe fitting 50, by sliding the flanges into the grooves and thereafter clamping the flanges against the tongues 49' by the use of screws 51 or other suitable means.

15 The passage of the water to the mixing chamber is controlled by a fuller ball 52 mounted on a rod 53 pivotally connected to an eccentric pin 54 on a shaft 55 journaled in the upper end 56 of the coupling 8. The 20 shaft 55 has a square end 57 to which an angled bracket 58 is secured by a nut 59, said bracket having a handle 60 secured thereto. The lower end 61 of the bracket 58 turns about the upper portion of the 25 coupling 8 and is limited in its movement by stops 62 and 63. When the bracket 58 is in contact with the stop 62 the water is shut off and when it is in contact with the stop 63 the valve is moved inwardly off its 30 seat to full open position.

Means are provided for operating the switch simultaneously with the turning on of the water consisting of a cam 64 journaled on the cylindrical end 56 of the coupling 35 and secured to the bracket 58 by the handle 60, said cam having a recess 61' to

permit movement of the button 41 to inoperative position when the water is shut off and connected to the surface 62 so that as the faucet is opened by turning the handle 40 40 the surface 62 is brought into contact with the button 41 to move it inwardly to close the contacts. Thus the switch acts in conjunction with the water valve to close the circuit to the ozonizing apparatus on the 45 turning on of the water.

What I claim is:

1. In a circuit closer, the combination with a block of insulating material and a pair of contacts mounted thereon, of a member secured to the block and having flanged extensions projecting from one side of the block, and screws for moving the flanges on said extensions into clamping engagement with a support. 50

2. In a circuit closer, the combination of a block of insulating material having a cavity in one side, coöperative switch contacts mounted in opposite sides of said cavity, a metal channel plate engaging the 60 side of the block opposite the cavity and the sides of the block adjacent thereto and having flanged extensions, and means passing through the plate and block to secure the flanges on said extensions in clamping 65 engagement with a support.

In testimony whereof I affix my signature in presence of two witnesses.

WILLIAM G. LINDEMANN.
